[57] **CLAIM**

The ornamental design for a razor display package, substantially as shown and described.

DESCRIPTION

FIG. 1 is a front elevational view of a razor display package showing my new design;
FIG. 2 is a rear elevational view thereof;
FIG. 3 is a view taken from the left side of FIG. 1;
FIG. 4 is a view taken from the right side of FIG. 1;
FIG. 5 is a view taken from the bottom of FIG. 1, the top being substantially a mirror image thereof; and
FIG. 6 is a front elevational view of a razor display package showing a further embodiment of my new design.
